(57) **CLAIM**

We claim the ornamental design for a display screen or portion thereof with graphical user interface, as shown and described.

DESCRIPTION

FIG. 1 is a first image for the display screen or portion thereof with graphical user interface, showing my new design;

FIG. 2 is a second image thereof;

FIG. 3 is a third image thereof; and,

FIG. 4 is a fourth image thereof.

The outermost broken lines in the figures show the display screen or portion thereof and form no part of the claimed design. The shorter broken lines and dotted broken line text in the figures show portions of the graphical user interface that form no part of the claimed design.

1 Claim, 4 Drawing Sheets
